US0D1070825S

(12) **United States Design Patent** (10) **Patent No.:** **US D1,070,825 S**
(45) **Date of Patent:** **** Apr. 15, 2025**

(54) **MICROPHONE**

(71) Applicant: **Shure Acquisition Holdings, Inc.**,
Niles, IL (US)

(72) Inventors: **Jase A. Ruggles**, Chicago, IL (US);
Michael Shane Nagel, Skokie, IL (US);
John Matthew Miller, Grayslake, IL
(US)

(73) Assignee: **Shure Acquisition Holdings, Inc.**,
Niles, IL (US)

(**) Term: **15 Years**

(21) Appl. No.: **29/894,118**

(22) Filed: **Jun. 6, 2023**

(51) **LOC (15) Cl.** **14-01**

(52) **U.S. Cl.**

USPC **D14/225**; D14/226

(57) **CLAIM**

The ornamental design for a microphone as shown and described.

DESCRIPTION

FIG. 1 is a front perspective view of a microphone showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines immediately adjacent to the shaded area define the bounds of the claimed design and form no part thereof. The broken lines depicting the remainder of the microphone form no part of the claimed design.

1 Claim, 8 Drawing Sheets
